UNITED STATES PATENT OFFICE

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

BOBBIN SUPPORT FOR WEFT-REPLENISHING LOOMS

Application filed August 10, 1929. Serial No. 384,853.

This invention relates to improvements in bobbin supports for weft replenishing looms and it is the general object of the invention to provide a simple form of element to hold 5 the bobbin support yieldingly in normal position.

Multicolor magazines for weft replenishing looms ordinarily employ in their construction a plurality of vertical stacks of bobbins beneath which are located inclined bobbin supports. The bobbins fall from one or another of the stacks onto the supports and roll to a common transfer position above the shuttle when the lay is in its foremost position. At 10 the time of transfer the supports yield slightly to permit the bobbins to pass between them. In the past this yielding has been provided for by a coil spring one end of which engages the support and the other end of which is received by a collar angularly and longitudinally adjustable on a tie rod of the magazine. It is an important object of my present invention to eliminate the collar and wind the 15 spring with coils of reduced diameter which will grip the tie rod.

It is a further object of my present invention to provide the spring with a wind that will permit it to be turned in one direction on the rod for angular adjustment but will resist movement in the opposite direction of the direction in which the spring yields when the bobbin support moves at the time of transfer.

With these and other objects in view which will appear as the description proceeds, my invention resides in the combination and arrangement of parts hereinafter described and set forth in the claims.

In the accompanying drawings wherein a 40 convenient embodiment of my invention is set forth,

Fig. 1 is a front elevation of the lower part of a magazine having my invention applied thereto,

Fig. 2 is a horizontal section on line 2—2 of Fig. 1,

Fig. 3 is a detail top plan view looking down on the spring which is at the lower right hand corner of Fig. 2, being the front right hand spring of the magazine, and

Fig. 4 is an end elevation taken in the direction of arrow 4, Fig. 1.

Referring to Fig. 1, I have shown a loom side or frame 10 on which is mounted foot 11 of the inside plate 12 of a multicolor magazine M. The magazine includes horizontal tie rods 12 which are parallel and support at their outer ends a bobbin tip supporting plate 14. It is to be understood that two or more vertical stacks of bobbins are disposed between the plates 12 and 14, the bobbins being substantially parallel with tie rods 13 and controlled by means of cradles not set forth therein but well understood. The cradles act to lower the bobbins from one or another of the stacks so that they move toward transfer position.

In order to hold a bobbin in transfer position for proper engagement with a transfer arm 15 I provide front and back links 16 and 17, respectively, which are loosely pivoted on the tie rods, there being one tie rod for each of said links. Bolts 18 pass through the lower ends of the links to provide pivotal connections for the front and back bobbin supports 19 and 20, respectively. These supports are held in position by means of set screws 21 which pass through lateral fingers 22 on the links to engage the plate 14. It is to be understood that the outer plate 14 has associated thereto two bobbin supports which are in front of and behind, respectively, the center of the magazine.

The rear support for the bobbin butt includes a link 23 which is loosely pivoted on the tie rod on which is mounted link 17. A bobbin support 24 is attached to the link 23, and a bobbin support 25 for the front of the bobbin butt may also be provided.

The supports for the bobbins herein described may be substantially the same as those shown in Patent 1,703,935 issued to Hume et al.

In carrying my present invention into effect I provide improved means for holding the supports 19, 20 and 24 yieldingly in normal or bobbin retaining position. As shown in Fig. 2 I provide a torsion spring 30 the right hand end 31 of which extends into the upper portion of the hub, preferably above

the tie rod. The spring then extends forwardly and to the left, being coiled around the front tie rod in a direction toward inner plate 12 in a counter-clockwise direction.

5 There are several coils 32 on this spring of relatively larger diameter than thickness of the tie rod, but at the left end of said spring I form several coils 33 of reduced diameter the internal diameter of which is slightly less than the diameter of the tie rod. The small coils grip the rod and hold the spring in place. During the time of transfer the support 19 as shown in Fig. 4 will move to the left, thereby winding the spring 32 in a direction to 10 tighten the small coils and prevent them from slipping.

15 In like manner I provide the rear link 17 with a spring 40 which is wound around the tie rod toward the plate 12 in a clockwise direction. It should be noted that spring 40 is 20 of the opposite hand or twist to that employed for the front support 19, this being desirable in view of the fact that the rear support 20 moves in a direction opposite to that in which support 19 moves at the time of transfer.

25 A third spring 50 is supported by the rear tie rod, and has engagement with the upper end of link 23. This spring is wound as shown particularly in Fig. 2 so that when the support 24 moves rearwardly the coils will be tightened with respect to the tie rod. In each of the springs 40 and 50 I provide coils 31 and 51 respectively which operate in a manner similar to coils 33.

30 33 In assembling the magazine employing my present improved form of spring the larger coils will be placed over the tie rod first and the spring turned in such a direction as to expand the coils after the smaller coils have engaged the tie rod. If the smaller coils are made of the correct diameter it would be found practically impossible to turn the springs on the tie rods in a direction which would tighten the coils. I do not wish to be 40 limited to this particular method of assembling the springs on tie rods.

45 From the foregoing it can be seen that I have eliminated the usual form of holder for the coil spring employed in connection with support of multicolor magazines by the simple expedient of winding certain of the coils of the torsion spring small enough so that they will grip the tie rods. It will further be seen that the hand or twist of the spring depends upon the type of strain it is called upon to resist, the connections between such that under the normal action of the magazine at the time of transfer the coils of the springs 50 will be tightened or compressed so that the loosening of the smaller coils is impossible. It will further be seen that by turning the springs in a direction the reverse of that in which they turn under normal bobbin passing 60 operation they may be adjusted longitudi-

nally and angularly with respect to the tie rods.

Having thus described my invention it will be apparent that changes and modifications may be made therein by those skilled in the art without departing from the spirit and scope of the invention and I do not wish to be limited to the details herein disclosed but what I claim is:

1. In a weft replenishing mechanism having a rod, a bobbin support pivotally mounted with respect to the magazine, and a coil spring surrounding the rod and having coils of two different diameters, the larger coils being operatively connected to the support to yieldingly resist movement of the latter at the time of transfer, and the smaller coils fitting tightly over the tie rod to grip the same and to resist movement of the spring relatively to the rod at the time of transfer. 75

2. In a weft replenishing mechanism having a rod, a bobbin support pivotally mounted with respect to the rod, a coil spring having relatively large coils at one end thereof and smaller coils at the other end thereof, 90 the smaller coils fitting tightly over the tie rod resisting angular movement of the spring relative to the rod, and the larger coils being connected to the support.

3. In a weft replenishing mechanism having a rod, a bobbin support pivotally mounted with respect to the magazine, a coil spring having relatively large and relatively small coils, the small coils tightly gripping the rod to resist angular movement relative thereto, 100 and the large coils being connected to the support and yielding under torsional strain to resist movement of the support yieldingly at the time of bobbin transfer.

4. In a weft replenishing mechanism having a rod, a bobbin support pivotally mounted with respect to the rod, a coil spring surrounding the rod and having relatively large and relatively small coils, the small coils tightly gripping the rod to resist angular movement relative thereto and the large coils being connected to the support and yielding under torsional strain to resist movement of the support yieldingly at the time of bobbin transfer, the coils being 110 wound in a direction to cause them to be tightened relatively to the rod when the support yields to permit transfer of a bobbin. 115

5. In weft replenishing mechanism having two spaced tie rods, a bobbin support pivotally mounted on each rod, said supports cooperating to support a bobbin in transfer position, and a pair of coil springs, one for each tie rod and corresponding support, said coil springs each having relatively small coils to grip the tie rods tightly and having relatively large coils operatively related to the supports to yield under torsional strain, said springs being of opposite hand. 120

6. In weft replenishing mechanism hav- 125

ing two spaced tie rods, the bobbin support pivotally mounted on each rod, said supports cooperating to support a bobbin in transfer position, and a pair of coil springs, one for each tie rod and corresponding support, said coil springs each having relatively small coils to grip the tie rods tightly and having relatively large coils operatively related to the supports to yield under torsional strain, one of said springs having coils wound in one direction and other of said springs having coils wound in opposite directions.

7. In weft replenishing mechanism having two spaced tie rods, the bobbin support pivotally mounted on each rod, said supports cooperating to support a bobbin in transfer position, and a pair of coil springs, one for each tie rod and corresponding support, said coil springs each having relatively small coils to grip the tie rods tightly and having also relatively large coils operatively related to the supports to yield under torsional strain, one of said springs having coils wound in right hand direction and the other springs having coils wound in left hand direction.

8. In weft replenishing mechanism having two spaced tie rods, the bobbin support pivotally mounted on each rod, said supports cooperating to support a bobbin in transfer position, and a pair of coil springs, one for each tie rod and corresponding support, said coil springs each having relatively small coils to grip the tie rods tightly and having relatively large coils operatively related to the supports to yield under torsional strain, said springs at the time the supports yield to permit transfer turning in opposite direction and having the coils thereof so disposed as to tighten with respect to the rods.

9. In a weft replenishing mechanism, a bobbin support movable to permit a bobbin to pass out of the mechanism, a coiled spring operatively connected to the support to yieldingly resist movement of the support, and a holder for the spring, certain coils of the spring being held by their own resilience to the holder to resist movement of the spring as a whole relatively to the holder.

50 In testimony whereof I have hereunto affixed my signature.

ELBRIDGE R. HOLMES.
